UNITED STATES PATENT OFFICE

95,969

DESIGN FOR A SHOE

Josef Lanz, Salzburg, Austria

Application May 2, 1935, Serial No. 56,665

Term of patent 7 years

To all whom it may concern:

Be it known that I, Josef Lanz, a citizen of Austria and resident of Salzburg, in the Province of Salzburg and State of Austria, have invented a new, original, and ornamental Design for a Shoe, of which the following is a specification, reference being had to the accompanying drawing, forming part thereof, in which,

Fig. 1 is a plan view of the shoe showing my new design; and

Fig. 2 is a side perspective view of the shoe shown in Fig. 1.

I claim:

The ornamental design for a shoe, as shown.

JOSEF LANZ.
